GLOVE HOLDER

Gertrude Bloom and Israel Bloom, New York,
N. Y., assignors to Gluv-Gard Mfg. Co., Inc.

Application November 10, 1949, Serial No. 126,464

1 Claim. (Cl. 24—73)

1

The invention herein disclosed relates to holders for ladies' gloves of the general type shown in copending patent application Serial No. 3,944 filed January 23, 1948, and comprising a glove encompassing form of clasp adapted for attachment to a lady's handbag or other convenient support.

Particular objects of the present invention are to provide a holder or carrier of this nature which may be readily attached to a handbag or the like, which will firmly and securely hold the gloves in a neat, compact bundle formation, which can be quickly and easily opened and closed, which will be of attractive, ornamental appearance, which will be small enough not to add objectionable bulk to the handbag or other support to which it may be attached and which, with all these desirable characteristics will be of simple sturdy construction and low cost.

Other desirable objects attained by the invention and details of the novel features of construction, combination and relation of parts are set forth and will appear in the course of the following specification.

The drawing accompanying and forming part of the specification illustrates a present practical embodiment of the invention. Structure, however, may be modified and changed in respect to the immediate illustration, all within the true intent and scope of the invention as hereinafter defined and claimed.

Fig. 1 in the drawing is a perspective view of the device as attached to and in use on a lady's handbag, the latter shown broken away;

Figs. 2 and 3 are enlarged front elevations showing the device in closed and open condition;

Fig. 4 is an edge view of the holder;

Fig. 5 is a further enlarged broken sectional detail of the ornamental roll-like handle on the end of one of the two companion clasp members;

Fig. 6 is a similar view of the same parts shown in separated relation;

Fig. 7 is a broken cross sectional detail of the clasp members on substantially the plane of line 7—7 of Fig. 4.

As shown in Fig. 1, the device is in the nature of a substantially ring-like clasp adapted to hold a pair of gloves 10 in a small, smoothly rolled, compact bundle formation suspended from a lady's handbag 11.

This clasp is shown attached to the handbag by means of a chain 12 looped about the handle 13 of the bag.

Specifically the clasp is shown as made up of a pair of companion ring-forming members 14, 15, pivotally connected together at one end as

2

by the transverse studs 16 on one member pivoted in the perforated spaced lugs 17 on the other member and releasably connected at the opposite end by a roll formation 18 on one member, releasably clasped in a substantially semi-circular spring jaw 19 on the other member.

The arcuate, ring-like glove gripping members 14, 15, may be made of spring metal stiffened in the intermediate curved portions of the same by arcuate embossments 20.

The hook element 19 on the one member is shown as having an out-turned lip 21 at the free end of the same to serve as a wedge for the entering roll member 18 and to afford a grip for the fingers to facilitate release and opening movement of the spring clasp construction.

The roll element 18 of the spring catch is shown provided by the formation of a circular loop 22, Fig. 7, on the end of jaw member 15.

For decorative purposes and added strength this loop is shown ornamented by knobs, discs or "jewels" 23 of colored glass, plastic or the like, held by the annular flanges 24 on metal discs or end caps 25 secured over the ends of the loop by an elongated tubular rivet 26.

In addition to their ornamental effect the projecting "jewels" 23 may serve as finger grips in the opening and closing movements of the clasp.

The complementary, oppositely disposed, arcuate jaw members 14, 15, open widely to freely receive the gloves and in closing, the roll abutment 18 on one member and companion spring hook 19 on the other member operate to roll and fold the gloves into fully grasped relation between the jaws. The indented ridge at 27, Fig. 2, at the pivotal connection between the members operates to center and grip the bundle formed by the compressed glove material, overcoming tendency of the gloves to slip one way or the other.

The device consists in the main of but the two simple clasp members and is therefore relatively inexpensive. These provide a ring-like structure of light weight and small dimensions. The arcuate embossments 20 hold these members to their curvilinear shape, localizing the spring effect to the yielding hook and engaging roll formations at the ends of the same. Furthermore, these embossments form transverse ridges in the sheet metal structure of the jaws, assisting in gripping and holding the gloves firmly in place.

50 What is claimed is:

The glove carrier herein disclosed and comprising companion, arcuate jaws in opposed, oppositely bowed relation forming a ring-like clasp for embracing a pair of gloves, the ends of said arcuate jaws meeting in opposing relation, the

meeting ends of the jaws at one side of the ring-like clasp being indented inwardly within the ring-like contour and pivotally connected together, leaving the exterior of the clasp free of projecting hinge formation and providing projections within the interior of the ring-like formation for gripping gloves held in the clasp, the other end of one of said jaws being rolled into a circular loop and the companion end of the other jaw being formed in a part circular, resilient hook to partially embrace said loop, said hook terminating in an outwardly projecting, inclined lug making sliding wedging engagement over the circular loop in the closing movement of the jaws and providing a projection for engagement by the fingers in forcing the hook back over the circular loop in the releasing operation of the jaws, projecting elements at opposite ends of the circular loop extending beyond the edges of the hook embracing the loop and providing projections at an angle to said projecting lug for engagement by other fingers effecting the release of the hook from the loop, and suspension elements connected with one of the jaw members adjacent said hook and adapted to be connected to form

5 a supporting loop opposite the hinge for suspending the clasp with the releasable hook at the top and the hinge connection at the bottom in the intended use of the article.
